United States Patent Office.

BEN F. DUNKLEE, OF CONCORD, NEW HAMPSHIRE, ASSIGNOR TO A. S. GEAR, OF NEW HAVEN, CONNECTICUT.

Letters Patent No. 96,407, dated November 2, 1869.

IMPROVEMENT IN STEP FOR VERTICAL SPINDLE.

The Schedule referred to in these Letters Patent and making part of the same.

To all whom it may concern:

Be it known that I, BEN F. DUNKLEE, of Concord, in the county of Merrimack, and State of New Hampshire, have invented a new Improvement in Step for Vertical Spindle; and I do hereby declare the following, when taken in connection with the accompanying drawings, and the letters of reference marked thereon, to be a full, clear, and exact description of the same, which said drawings constitute part of this specification, and represent in—

Figure 1, a side view, and in

Figure 2, a vertical central section.

This invention relates to an improvement in the step or bearing for rapidly-revolving vertical spindles; the object being to construct a bearing which shall be self-lubricating; to this end,

The invention consists in setting the step into a socket, the said step being perforated through its lower end, and opening into a chamber beneath, and the said chamber beneath communicating with the chamber at its side; the outside chamber extending up above the top of the step, with the communication from the said outside chamber, to the step over its upper edge, so that the outside chamber, being filled with oil, supplies the inner chamber, and as the spindle setting in the step revolves, the oil will pass up through the perforations in the step, and be drawn up by the centrifugal force of the step, and pass out again into the outer chamber, and so continue keeping the step constantly lubricated with fresh material.

In order to the clear understanding of my invention, I will fully describe the same as illustrated in the accompanying drawings.

A is a socket arranged to receive and hold the step B, and so as to form a chamber C beneath the said step, and an opening, a, is formed through the step into the chamber C beneath.

Upon the side of the socket A is arranged a verti-

cal chamber, D, extending up above the top of the step, and communicating with the chamber C through an opening, d, and also with the step over its top through an opening, c.

E is a spindle resting in the step.

The lubricating-material is poured into the chamber D until it is filled to the line f, the spindle rapidly revolving creates a centrifugal force within the step, which draws the oil through the opening a from the chamber beneath, and causes it to work up, and flow over the top of the step, through the opening c, back into the chamber D.

In order to insure a free passage through the step, I form one or more slight vertical grooves in the step, as seen in figs. 2 and 3.

For convenience of cleaning from any sediment which may have found its way into the chamber, I fix a plug, F, at the bottom, which, being taken out, all the sediment may be removed, and to clear out the passage d, I insert a screw or plug, h, which, being removed, communication is had to the said passage d.

I am aware of the patent of Frank Douglass, June 9, 1868, and do not wish to be understood as claiming anything contained therein.

Having fully described my invention,

What I claim as new and useful, and desire to secure by Letters Patent, is—

1. The combination of the two chambers D and C, constructed together in one and the same piece, with the step B, arranged in one of the said chambers, and with the passages a c d, all operating as and for the purpose set forth.

2. In combination with the above, the plug F, as and for the purpose specified.

BEN F. DUNKLEE.
